CLAIM

The ornamental design for a television receiver, as shown and described.

DESCRIPTION

FIG. 1 is a perspective view of a television receiver showing our new design;

FIG. 2 is a front view thereof where the rear view is a mirror image;

FIG. 3 is a left side view thereof where the right side view is a mirror image;

FIG. 4 is a top plan view thereof where the bottom plan view is a mirror image;

FIG. 5 is a part-in enlarged perspective view of the left-lower part of the front side; and,

FIG. 6 is a part-in enlarged front view of the left-lower part of the front side.

The broken lines depict portions of the television receiver that form no part of the claimed design. The dash-dot broken lines define the bounds of the claimed design and form no part thereof.

1 Claim, 6 Drawing Sheets
